US00D789015S

(12) **United States Design Patent** (10) **Patent No.:** **US D789,015 S**
Shu et al. (45) **Date of Patent:** **** Jun. 6, 2017**

(54) **LIFTING CYLINDER WITH BALANCED VALVE**

(71) Applicant: **Ningbo Yinzhou Zhongtian Hydraulic Co., Ltd.**, Ningbo (CN)

(72) Inventors: **Pingguo Shu**, Ningbo (CN); **Chengshu Jiang**, Ningbo (CN); **Yihai Zhong**, Ningbo (CN)

(73) Assignee: **Ningbo Yinzhou Zhongtian Hydraulic Co., Ltd.**, Ningbo (CN)

(**) Term: **15 Years**

(21) Appl. No.: **29/571,293**

(22) Filed: **Jul. 15, 2016**

(51) LOC (10) Cl. **12-05**

(52) U.S. Cl.

(57) **CLAIM**

The ornamental design for a lifting cylinder with balanced valve, as shown and described.

DESCRIPTION

FIG. 1 is a perspective view of a lifting cylinder with balanced valve, showing our new design;

FIG. 2 is a left side view thereof;

FIG. 3 is a right side view thereof;

FIG. 4 is a front view thereof;

FIG. 5 is a rear view thereof;

FIG. 6 is a top view thereof; and,

FIG. 7 is a bottom view thereof.

The dashed lines are included for illustrating environmental structures and form no part of the claimed design.

1 Claim, 4 Drawing Sheets
